UNITED STATES PATENT OFFICE.

ELON A. NELSON, OF CHICAGO, ILLINOIS.

PAPER HOLDER.

Application filed February 1, 1926. Serial No. 85,120.

The invention relates to note paper holders, and particularly to the kind where a roll of paper is drawn over a smooth surface so that memoranda may be written 5 upon the exposed portion of the paper.

It is an object of the invention to provide a device of the character described in which the exposed paper portion is held taut so that memoranda may be written upon it 10 without requiring the use of the left hand to hold the paper in place.

A further object aims to provide automatic means for maintaining the exposed paper portion in taut condition.

15 A still further object aims at providing resilient means for securing one end of the exposed paper portion in place and gravity actuated means for holding the other end in place so that the paper web is held in 20 stretched or taut condition.

Another object constitutes the provision of means for holding the free paper end and imparting thereto a curl, so that upon the release of the holding means the curled paper 25 unwinds and facilitates the grasp thereof.

A further object constitutes the provision of a device which is of simple and inexpensive construction and may be utilized also as 30 a pen and pencil holder and as a desk calendar.

With the foregoing and other objects in view which will appear as the description proceeds, the invention resides in the arrangement and combination of parts described in the following specification, particularly pointed out in the claims forming a part thereof, and illustrated in the drawings, in which:

40 Figure 1 is a plan view of the device constructed in accordance with my invention;

Figure 2 is a side view thereof;

Figure 3 is a longitudinal section on the line 3—3 of Figure 1; and

45 Figure 4 is a cross-section on the line 4—4 of Figure 2.

Referring to the drawing, the body or frame of the holder is formed from a solid block 10 of wood or equivalent material and provided with an inclined plane 11. The larger end 12 is cored out as at 13.

50 A plate 14 of metal or other preferred or suitable material is secured to the upper surface of the block by screws 21 and is co-extensive therewith. Attention is called to the fact that the thin end of the block 10

is rounded as at 15 for a purpose hereinafter further explained. The large end of the block is encased by side walls 16 and 17 and an end wall 18 which walls abut the 60 block and form a chamber. The side walls are provided at the upper end with registering grooves 19 for the reception of pencils or pen holders as indicated in dotted lines in Fig. 1. The side walls terminate in slanting 65 front edges 20 and are provided on the inner side and parallel to said edges 20 with grooves 22 which are in registering relation and afford a runway for a slide 23 terminating at the upper end in a flange 24 and at 70 the lower end in a flange 25.

The forward end of the block, as stated before, is rounded at 15 and a clamping plate 26 of the same contour as the rounded end is fitted thereon to closely hug the same. 75 The plate 26 has side arms 27 and 28 which are pivotally secured to the sides of the block 10 by screws or pintles 29. The arm 28 is extended at 30 and equipped with a treadle or thumb piece 31.

80 The block 10 is provided with a cored out portion 32 terminated at one side in a slot 33 (Fig. 2) and at the other side in a hole 34 for the reception of a spring wire 35 which is secured to the convex bottom 36 of 85 the cored out portion 32 and extends through the slot 33 into an aperture provided in the arm extension 30 so that normally the thumb piece 31 is raised and the bar is held in clamping relation on the block. The entire 90 device is mounted on a base plate 37. The slide 23 is provided with a calendar 38 and thus the device is serving the function of a desk calendar in addition to its function as a writing pad.

95 In use a roll of paper 40 is deposited in the cored out portion 13 of the block and the paper web 41 is threaded between the slide 23 which is held in position by its gravity and the block and covers the inclined surface 100 of the block and terminates between the clamping plate and the block corner 15. The pressure of the clamping plate holds the free end of the paper web secure, whereas the slide 23 under its weight rests with its 105 flange 25 on the paper web at the upper end of the inclined surface, so that the exposed paper portion is held taut and may be written upon without the necessity of holding the paper down. This is of special advantage 110 when memoranda are written while the writer receives a message over the telephone.

When it is desired to tear off the exposed paper portion, the thumb piece 31 is depressed so that the clamping bar is raised. The paper end between the bar and the block having been provided with a downward curl will upon release curl up as shown in dotted lines in Figure 3, facilitating thereby the grasp of the free paper end 42 and withdrawal of the paper. As soon as 10 the proper length of paper has been withdrawn, the clamping bar is released to clamp the paper onto the block, and the paper is then torn off along the outer end of the clamping bar. In withdrawing paper from 15 the roll, the slide 23 is slightly raised under the pull of the paper, and no noticeable resistance is offered to the withdrawal of the paper, since the slide rests on the paper web only under its gravity.

20 While the drawing shows a preferred embodiment of the invention, numerous changes and alterations may be made within the purview of the invention. I, therefore, do not limit myself to the details of construction as shown, but include all changes, rearrangements and modifications falling within the scope of the invention as defined in the appended claims.

I claim:

- 30 1. A paper holder, including a support for the paper, automatic means for holding one end of the paper, and automatic means for drawing the other end of the paper so as to maintain the paper on the support in taut condition.
- 35 2. A paper holder, including a support for the paper, gravity actuated means on said support for holding one end of the paper, and automatic means for drawing the other end of said paper so as to maintain the paper on the support in taut condition.
- 40 3. A paper holder, including a support for the paper, gravity actuated means on said support bearing on one end of the paper, and resilient automatic means for drawing the other end of the paper so as to maintain the paper on the support in taut condition.
- 45 4. A paper holder, including a support for the paper, gravity actuated means on said support for holding one end of said paper, and resilient automatic means pivotally secured to said support for drawing the other end of the paper so as to maintain the paper on the support in taut condition.
- 50 5. In a paper holder, a support having a rounded corner, and a clamping bar pressing the paper onto said corner to thereby impart a curl to the paper end.
- 55 6. A paper holder, including a support

having a chamber and a writing surface adjacent thereto, said chamber housing a roll of paper and permitting unwinding over said writing surface, gravity means at one end of the writing surface to hold the paper, and automatic means at the other end of the writing surface to draw the paper taut on said writing surface.

7. A paper holder, including a support 70 having a chamber and a writing surface adjacent thereto, said chamber housing a paper roll and permitting unwinding of the roll over said surface, a substantially vertical slide forming one wall of said chamber and adapted to rest on the paper, and means at the remote end of said writing surface for maintaining the paper on the writing surface in taut condition.

8. A paper holder, including a support, 80 having a chamber and a writing surface adjacent thereto, said chamber housing a paper roll and permitting unwinding of the roll over said surface, a substantially vertical slide forming one wall of said chamber and adapted to rest on the paper, and spring actuated means acting on the other end of the paper for maintaining the paper on the writing surface in taut condition.

9. A paper holder including a support for 90 holding a roll of paper, said support having a writing surface over which the paper unwinds, means at one end of said surface for holding the paper, and means at the other end of said surface for automatically drawing the paper taut.

10. A paper holder for a roll of paper, including means for holding an intermediate portion of the paper, and means for automatically drawing the end of the paper taut. 100

11. A paper holder for a roll of paper, including a support having a writing surface over which the paper unwinds, and a rounded corner at the end, gravity means adjacent the paper roll for holding the 105 paper, and means pivotally secured to said support for tensioning the paper on said writing surface and maintaining the paper in taut condition.

12. A paper holder for a roll of paper, 110 including a support having a writing surface over which the paper unwinds, and a rounded corner at the free end, gravity means adjacent the paper roll for holding the paper, and a clamping bar pivotally secured to said support and conforming to said corner for tensioning the paper on said writing surface and maintaining the paper in taut condition.

In witness whereof I affix my signature.

ELON A. NELSON.
